UNITED STATES PATENT OFFICE.

BERTHA M. STRADLING AND EMMA E. WASHBURN, OF BLAIR, NEBRASKA.

ADJUSTABLE ABDOMINAL SUPPORTING-CORSET.

1,301,618.

Specification of Letters Patent. Patented Apr. 22, 1919.

Application filed June 17, 1918. Serial No. 240,417.

To all whom it may concern:

Be it known that we, BERTHA M. STRADLING and EMMA E. WASHBURN, citizens of the United States of America, residing at Blair, in the county of Washington and State of Nebraska, have invented certain new and useful Improvements in Adjustable Abdominal Supporting-Corsets, of which the following is a specification.

Our invention relates to improvements in corsets worn by patients afflicted with sagging viscera or having heavy abdominal walls resulting in a pendulous abdomen, for those who have undergone abdominal operations for any of the numerous disorders requiring such treatment, and where, in such cases scar formation is imperfect as the result of required drainage; and among the principal objects of our improvements are the following:

To provide a substantially topless corset, that is, one not appreciably extending above the waist line, so as to interfere with abdominal breathing, that will, with comfort to the wearer, sustain such other garments as are necessarily imposed thereon or attached thereto; and that, as a garment of this character for general wear, will adjust itself to the different poses assumed by the wearer, either in active work or in those comfortable positions selected for bodily repose.

A further object is to facilitate changing the position of application and direction of action of the abdominal supporting parts, without in any manner disturbing the position or adjustment of the supporting base or body part of the corset; also, to provide this abdominal supporting part with means independent of its attaching means, for adjusting its encompassing capacity, for such abdominal changes as may occur during pregnancy; and to adjust its force of compression on the parts supported, in cases where more pressure is required than that which is necessary to simply support; that is, compression sufficient to raise the sagging viscera to a normal position.

And further, to provide smooth and pliable surfaces in all parts of the structure that are disposed to contact with or bear against lines of incision made in the most important abdominal operations; for instance, the median vertical line of the abdomen and the position in the lower right quadrant thereof peculiar to operations for appendicitis. Also, to grade and dispose the bonings and

busks, for size and pliability, in accordance with the peculiar requirements hereinafter more particularly set forth.

We attain these and other minor objects to be more specifically disclosed, by the mechanism and structure illustrated in the accompanying drawings in which—

Figure 1, is a front elevation of the corset, laced, hooked and fastened at one of its peculiar adjustments for service; Fig. 2, a side elevation, at adjustment the same as in Fig. 1; Fig. 3, a cross-sectional view on the broken line A of Figs. 1 and 2; Fig. 4, a cross-section or plan taken on the broken line B in Figs. 1 and 2; and Fig. 5, shows a cross-section through the central front on the broken line C of Figs. 1 and 2. In all of which views the same numerals refer to like parts.

The back 6 extending between the opposite side seams 8 and 8, is all constructed of a nonelastic fabric and shaped to perfectly fit the entire upper curve of the hips, the small of the back, and all of that portion of the wearer's body lying between said side seams. The central top or summit 5 of this back is extended above the waist line for spinal support and to assist in obviating upward movement of the corset when the wearer's position is that of reclining. From this summit the top edge is sloped downwardly and carried forwardly in easy curves connecting with the top edge of the front close down to the waist line, leaving the arms and bust of the wearer entirely free. Thin light resilient bonings, as indicated at 7, in suitable casings, prevents the back from shortening into laterally ranged wrinkles without destroying its flexibility to accommodate the bending movements of the wearer. This closely fitted non-elastic but pliable back serves as the constant supporting base for the connected adjustable and movable front portions of the corset, including its special abdominal support.

The front of the body consists of minor and major flaps connected by the vertical row 10 of separable fastenings, disposed about midway between the center of the front and the lefthand side seam 8. This separable connection serves as the regular opening for putting the corset on and off. The minor flap consists of the single section 9 of nonelastic fabric having its back edge permanently secured in the left side seam and its opposite free edge suitably finished

and provided with parts of the separable fastenings complementary to parts attached to the free edge of the major flap.

The major flap comprises a base section 11 of the same size, reversely shaped and disposed oppositely to the section 9 and made of like nonelastic material; its back edge is securely stitched into the opposite or right-hand side seam 8. A large central portion of 10 the front consists of the two opposite side sections 13 and 14 shaped from an elastic fabric. The right section 13 has its attached edge securely stitched into the boning shield 12 connecting it permanently to the outer 15 edge of the base section 11. The opposite left section 14 has its outer edge,—which is the free edge of the major flap,—finished with a light pliable busked edge and complementary parts of the separable fastenings 20 in the vertical row of fastenings 10. The adjacent centrally disposed edges of these elastic sections are provided with the vertical rows of spaced eyelets 15 and 15 to receive the lace 16. By this lacing the circumferential adjustment of the corset body is effected by varying the width of space between the adjacent edges of the elastic sections. It is obvious that this space must always be at the center of the front of the 25 applied corset, even though the body adjustments are attained by varying the length of this major flap.

The construction of the busked lacing edges through which are seated the vertical 30 rows of eyelets 15, are shown in enlarged cross-section in Fig. 4. Wide binding strips 35 and 35, are each folded laterally upon itself in the usual manner; and the opposed edges of the elastic sections 13 and 14 are 35 each stitched between the edges of one of the binding strips. In the resulting loop of each strip the pair of thin pliable bones 7 and 7 are disposed spaced apart, one in the outer edge of the loop and the other against 40 the stitched-in edge of the section. Through the space between the bones, lines of stitches placed close to the bones, close the opposite thicknesses of each doubled binding together to retain the bones in position; and the eyelets are disposed centrally through the space 45 between these seams.

The variable space between the lacing busks is backed by the detachably and adjustably supported lacing shield 17. This 50 shield consists of two thicknesses of a very light pliable fabric stitched with vertical seams to form casings for the longitudinal thin needle bones 18, 18 etc. At central points near its top and bottom ends socket 55 snaps or fasteners 19 are attached. Complementary parts of these snap fasteners are set in the center of the horizontally disposed elastic straps 20. Smaller like ball and socket fasteners 21 and 22, have a ball 60 part 21 seated in the lacing busks, as shown; 65 part 21 seated in the lacing busks, as shown;

and a longitudinal row of complementary sockets 22 disposed toward the ends of each strap, facilitates making such adjustments of the length of the straps as are not attained by their elasticity; and enables placing and retaining the shield at the exact center of the front, as well as supporting it against slipping endwise either downwardly or upwardly.

The lower edge of the flaps, of the whole 75 corset body front, is cut away, as shown, to a single arch form, spanning nearly the entire distance from one side seam 8 to the other. This allows the wearer perfect freedom to sit down or flex the thighs forwardly 80 and upwardly, without thrusting the lower edge of the front of the low-seated corset into the groins or thighs. It is obvious that the weight of the fabrics used in this body structure may be graded, according to the 85 requirements, from the heaviest to that which is very light even to porous or open mesh. And that the elastic sections yield edgewise to any tortuous movements of the front, as well as to compensate the temporary 90 abdominal expansion or inflation, caused by overeating or bloating, without resorting to changes in the centrally disposed lacing. Garment supporting straps 36 and 36, extending downwardly from the lower 95 ends of the lacing busks may have any suitable tip fastenings such as are usually used.

The right and left lappets 23 and 24 respectively, that form the adjustable abdominal support, have their wide bases 37 and 37 stitched into the side seams 8 and 8, each as shown in Figs. 1, 2 and 3. These lappets are irregularly tapered, toward their forward meeting and connecting ends, to a 100 desired width and at any adjustment of height, at their central front, they overlap the vertex of the arch of the lower edge of the body front; and according to the angular adjustment extend less or more below 105 and somewhat under said lower edge, when the wearer is standing erect or lying straightened. The free narrowed connecting end of the right lappet 23 overlaps the corresponding free end of the left lappet and extends 110 beyond the front center of the corset. A terminal portion of this free end is separated from the attached part and worked to form the short vertical lacing busk or edge 25, in which is incased the base of the wide flat 115 hook 26, to releasably engage the flat catch-bar 27 attached on the outside of the left lappet 24. The narrow terminal of the attached part is worked to form a like opposed lacing edge or busk 38; each busk has 120 a vertical row 42 of eyelets, as shown, to receive the lacing 28. These lacing busks are disposed substantially at the center of the front and by this lacing the combined length 125 of the lappets and the lifting pressure of 130

the abdominal support is adjusted. The free end 29 of the left lappet is extended beyond the flat catch-bar 27 sufficiently to underlap the lacing and busked eyeleted edges at all 5 adjustments, to supply a smooth shield therefor.

The wide bases of these lappets are slashed downwardly from the top edges, nearly the whole width, to open and form the adjustable lacing gores 30 and 30. This leaves the narrow unsevered portions 39 and 39, which are reinforced and stitched as shown; and are sufficiently flexible edgewise to serve as pivots to the bases of the lappets. Swing- 10 ing edgewise on these pivotal portions the lappets may be moved downwardly, at their connected front, to the positions indicated by the broken lines 31, 31 etc., to change both the position and direction of support. 15 20 The edges made by slashing the bases of the lappets are worked to form the eyeleted busks 40, properly boned or steeled as shown, to receive the laces 41 and 41. It is obvious that by slackening or drawing in these 25 lacings, gores of different angles are formed in accordance with the different angular adjustments of the abdominal support; and these gores sustain the full widths of the lappet bases for any adjustment, without 30 35 40 45 50 55 60 65 70 75 80 85 90 95 100 105 110 115 120 125 130 135 140 145 150 155 160 165 170 175 180 185 190 195 200 - of the wearer and the lower edge of the front arched to clear the forwardly-flexed thighs; an abdominal support consisting of opposite outside lappets having broad bases 5 secured in the vertical side seams that connect said back and front, vertical bonings disposed in casings shaped in connection with the parts of said side seams that secure the bases of the lappets and limited in their 10 downward extension to points not lower than the hip joints of the wearer, and means to adjustably and releasably connect the free ends of said lappets across the arched lower edge of said front.
- 15 5. An adjustable abdominal supporting corset, comprising a body having a vertical opening, suitable separable fastenings to releasably connect the opposite edges of the opening, an abdominal support consisting 20 of lappets having broad bases attached to the sides of said body, a terminal section comprising an eyeleted lacing busk and a flat hook, an eyeleted lacing busk on the free end of one lappet, a lace disposed in said 25 eyeleted busks to adjust the length of the lappet, a bar-eye on the opposite lappet to receive the flat hook and the terminal end of this lappet extended to underlap said
- lacing and busks, lacing gores disposed in the top edges of the lappets and garment 30 supporter straps on their lower edges.
6. An adjustable abdominal supporting corset, comprising a back, a minor front flap attached to one side of said back, a major front flap attached to the opposite side of 35 said back, suitable fastenings to releasably connect the opening edges of said flaps, the lower edges of the flaps curved to arch the bottom of the front, a lacing disposed to divide the major flap vertically for circumferential adjustment, an abdominal support 40 consisting of opposite lappets having broad bases attached to the connected sides of said back and front, means to releasably connect the free ends of said lappets, lacing means 45 in one lappet to adjust the encompassing length of the support, and lacing gores disposed downwardly into the top edges of said lappets to facilitate the edgewise swing thereof to adjust the height and the direction of the pressure of the support.

In testimony whereof we have hereunto affixed our signatures.

BERTHA M. STRADLING.
EMMA E. WASHBURN.
